United States Patent Office

Des. 233,596
Patented Nov. 12, 1974

233,596

PACKAGE OF SPOONS OR THE LIKE

Samuel R. Davis, Jr., and Harry A. Watson, Federalsburg,
Md., assignors to Ipcos Hospital Supply Corporation,
Valhalla, N.Y.

Filed June 29, 1972, Ser. No. 267,366

Term of patent 14 years

Int. Cl. D9—99

U.S. Cl. D9—193

FIG. 1 is a plan view of a package of spoons or the like showing our new design;

FIG. 2 is a side elevational view thereof;

FIG. 3 is an end elevational view thereof; and

FIG. 4 is an enlarged fragmentary perspective view thereof.

The side opposite the side shown is plain.

We claim:

The ornamental design for a package of spoons or the like, substantially as shown and described.
